MULTIPLE CONTROL FOR BRAKE
MECHANISM

Bruno L. Lonngren, South Milwaukee, Wis., assignor to Bucyrus-Erie Company, South Milwaukee, Wis., a corporation of Delaware

Application July 30, 1948, Serial No. 41,641

11 Claims. (Cl. 188—105)

1 My invention relates to new and useful improvements in brakes and control mechanisms therefor, more particularly to control mechanisms of hydraulic or pneumatic brakes.

Although useful in other relations, this invention may be employed to particular advantage in the control of power excavators, cranes and the like.

The principal objects of my invention are to provide brake control means such that:

- (1) The brake is automatically set when the fluid or other normal actuating means fails to function.

- (2) The actuated live end of the braking means is automatically reversed upon reversal of rotation of the drum.

- (3) The direction of the resultant force applied to the braking means is automatically reversed upon reversal of rotation of the drum.

- (4) The brake is readily convertible from a two-way to a one-way brake and vice versa without any addition or substitution of elements.

In addition to the objects above stated, I have worked out a number of novel and useful details, which will be readily evident as the description progresses.

My invention consists in the novel parts, and in the combination and arrangement thereof, which are defined in the appended claims, of which one embodiment is exemplified in the accompanying drawings, which are hereinafter particularly described and explained.

Throughout the description, the same reference number is applied to the same member or to similar members.

Referring now to the accompanying drawings, it will be seen that:

Figure 1 is a general side elevational view of a band-type brake with control mechanism constructed in accordance with the present invention.

Figure 2 is an end elevation, taken along the line 2—2 of Figure 1.

Figure 3 is a vertical section, taken along the line 3—3 of Figure 2, showing the means for braking clockwise rotation of the drum.

Figure 4 is a schematic plan view showing the operating valves and pneumatic circuit for the brake-control cylinders.

Referring now to Figures 1 to 3, we see that on frame 11a is mounted drum 12 over which passes a brake band 13 one end of which is secured, as at rock shaft 14, to frame 11a, while the other end is secured, as at 15, to lever 16 which is pivoted on frame 11a, as at rock shaft 14. At its

end, as at pin 17 (see Figure 3), lever 16 is adapted to be moved by piston rod 18 of operating cylinder 19 which is pivotally mounted at 20 on cylinder support 21 on base 11. When the piston rod 18 moves downwardly under pressure in the cylinder chamber, lever 16 moves to set the brake (clockwise rotation of lever 16 about rock shaft 14). Compression spring 22, also mounted on support 21, acts on rod 23 which is secured to lever 16 at 24 adjacent piston 18, to urge the lever 16 to brake-releasing position (counterclockwise rotation of lever 16 about rock shaft 14). Cylinder 19 is a conventional single-acting air cylinder supplied with compressed air from a conduit 25 (Figure 2) which leads to a control valve hereinafter described.

It will be noted that counterclockwise rotation of drum 12 tends to release the brake, since tension in brake band 13 tends to rock lever 16 into 20 brake-releasing position (even against the brake-setting force of piston 18), whereas clockwise rotation of drum 12 tends to set the brake (working with piston 18 to overcome spring 22). Hence, if only the cylinder-piston assembly 18—19, which 25 exerts only clockwise tension on the brake band, is used, the brake acts as a one-way brake, being effective to brake only clockwise rotation of drum 12.

To make the above-described one-way brake also effective as a two-way brake, I employ a second cylinder-piston assembly and lever to exert counterclockwise tension on the brake band, as will now be described (see Figure 1). Adjacent the dead-ended portion of brake band 13, lever 26 is pivotally connected at its end 27 to rock shaft 28 on main frame 11a. Connecting rod 29 is secured at its lower end to lever 26 as at 31, adjacent end 27, and has at its upper end an adjustable crosshead 31 which is adapted to bear against lug 32 on brake band 13 and to exert counterclockwise tension on the brake band when the rod 29 is in tension. At its end 33, lever 26 is adapted to be moved counterclockwise by piston 34 of cooperating cylinder 35 which is pivotally mounted at 39 on support 37 on base 11. Compression spring 38, also mounted on support 37, acts on rod 29 to hold it normally in brake-released position. A slot 39 is provided at the dead-end of brake band 13 on rock shaft 14, to allow counterclockwise play of this end of the band when lever 26 is urged counterclockwise to set the brake. Stop 21a (Figure 3) serves through lever 16, to dead-end the band 13 when the drum 12 rotates counterclockwise. The cylinder 35 is a conventional single-acting air cyl-

inder supplied with compressed air from conduit 40 which leads to a control valve as hereinafter described.

Turning now to Figures 1 to 3, we see that the safety control for the brake consists of a heavy spring 41 (Figures 1 and 2) mounted on support 21 and capable when released of setting the brake through spring washer 42, rod 43, bell-crank arm 44, bell-crank shaft 45 (Figure 2), and bell-crank arm 46 (Figure 3) which when released bears down on pin 17 at the end of brake lever 16 to set the brake. Spring 41 is, however, normally held compressed by rods 47 of a conventional single-acting air-brake cylinder 48 having a piston (not shown) preferably, though not necessarily, of diaphragm type. Rods 47 are fixed to the cylinder 48 which moves upwardly to compress spring 41, when piston rod 47, which is attached to support 21, is extended under air pressure. When the air supply fails, or when air is intentionally cut off (as when the machine is not in use), spring 41 is released to active position causing the brake to set.

Referring now to Figure 4, we see one of several possible circuits for controlling the pistons of cylinders 19, 35 and 48. Air to both cylinders 19 and 35 is supplied through conventional compensating valve 49 from pressure chamber 52, and to cylinder 48 through separately-controlled valve 50. When compensating valve 49 is in closed (brake released) position, exhaust from cylinders 19 and 35 passes out through outlet 53 which is automatically closed when valve 49 is opened (to set the brake). Valve 51 between cylinders 19 and 35 operates, when open, to permit valve 49 to control both cylinders as a two-way brake, and when closed to permit control of cylinder 19 alone as a one-way brake. Valve 50, normally open during operation, to set the safety brake control in case air pressure should fail, is usually closed when the machine is not in operation.

Having now described and illustrated one form of my invention, I wish it to be understood that my invention is not to be limited to the specific form or arrangement of parts herein described and shown.

I claim:

1. In a brake, the combination of: a brake drum; a brake-band frictionally engageable with the drum; first means dead-ending one end of the brake-band against movement in one direction when the drum pulls the brake-band in that direction; first actuating means operatively connected to the other end of the brake-band for setting and releasing the brake-band; second means, independent of said first actuating means, dead-ending said other end of the brake-band against movement in the opposite direction when the drum pulls the brake-band in said opposite direction; and second actuating means operatively connected to said one end of the brake-band for setting and releasing the brake-band.

2. A brake according to claim 1, further characterized by having means interconnecting the first and second actuating means for selective operation of one or both of said first and second actuating means.

3. A brake according to claim 1, further characterized by the fact that each brake actuating means includes a fluid operated cylinder-piston assembly, said cylinder-piston assemblies having normally interconnected pressure chambers.

4. In a brake, the combination of: a brake drum; a brake-band for friction engagement with

the drum; normally released first brake-setting means operatively connected with a live end of the brake-band; first fluid pressure means to actuate the first brake-setting means to set the brake; normally set second brake setting-means operatively connected to the live end of the brake-band; second fluid pressure means to actuate said second brake-setting means to unset the brake; a common fluid pressure source for the two fluid pressure means; a fluid pressure conduit to connect the source at will to the first fluid pressure means; and a fluid pressure conduit normally connecting the source to the second fluid pressure means; whereby failure of the pressure supply of the first fluid pressure means will permit the second brake-setting means to set the brake.

5. A brake according to claim 4, further characterized by the fact that the first brake-setting means is spring released and that the second brake-setting means is spring set.

6. A brake according to claim 4, further characterized by having means to disconnect the source at will from the second fluid pressure means, whereby the second brake-setting means can be locked in set position when the brake system is not being operated.

7. In a brake, the combination of: a brake-drum; a brake-band frictionally engageable with the drum; first means dead-ending one end of the brake-band against movement in one direction when the drum pulls the brake-band in that direction; first actuating means operatively connected to the other end of the brake-band for setting and releasing the brake-band; second means dead-ending said other end of the brake-band against movement in the opposite direction when the drum pulls the brake-band in said opposite direction; second actuating means operatively connected to said one end of the brake-band for setting and releasing the brake-band; and means interconnecting the first and second actuating means for selective operation of one or both of said first and second actuating means.

8. In a brake, the combination of: a brake drum; a brake-band frictionally engageable with the drum; means dead-ending one end of the brake-band against movement in one direction when the drum pulls the brake-band in that direction; first brake-setting means for setting the brake by motion of the other end of the brake-band to hold the drum against movement in said direction; a fluid-operated cylinder-piston assembly for actuating said first brake-setting means; means dead-ending said other end of the brake-band against movement in the opposite direction when the drum pulls the brake-band in said opposite direction; second brake-setting means for setting the brake by motion of said one end of the brake-band to hold the drum against movement in said opposite direction; and a second fluid-operated cylinder-piston assembly for actuating said second brake setting means; said cylinder-piston assemblies having normally interconnected pressure chambers.

9. In a brake, the combination of: a brake drum; a brake-band frictionally engageable with the drum; means dead-ending one end of the brake-band against movement in one direction when the drum pulls the brake-band in that direction; first brake-setting means for setting the brake by motion of the other end of the brake-band to hold the drum against movement in said direction; means dead-ending said other end of the brake-band against movement in the opposite direction when the drum pulls the brake-

band in said opposite direction; and second brake-setting means for setting the brake by motion of said one end of the brake-band to hold the drum against movement in said opposite direction; said second brake-setting means comprising means which is adaptable to engage the brake-band adjacent said one end thereof but is normally out of engagement therewith, and means for actuating said engaging means to tighten said band by moving said one end thereof in said opposite direction; and the second-mentioned dead-ending means comprising stop means for said other end of the band, said stop means being brought into engagement by motion of said other end of the band in said opposite direction.

10. A brake according to claim 9, further characterized by the fact that the first-mentioned dead-ending means is a slip connection, to permit brake-setting movement of said one end of the band when said other end of the band is dead-ended by the second-mentioned dead-ending means.

11. In a brake, the combination of: a brake drum; a brake-band for frictional engagement with the drum; a slip connection for dead-ending one end of the band against movement in one direction when the drum pulls the band in

that direction; a pivoted rocker-arm, on which the other end of the band is pivotally anchored; means to rock this arm to set or release the brake by motion of said other end of the band, 5 whereby to hold or release the drum against or for rotation in said one direction; stop means for the rocker-arm for dead-ending said other end of the band against movement in the other direction when the drum pulls the band in said other direction; a contact member on the band adjacent its said one end; a second contact member normally out of engagement with said first contact member; and means to cause said second contact member to engage said first contact member and apply pressure thereon to move said one end of the band in said other direction to hold the drum against rotation in said other direction.
